UNITED STATES PATENT OFFICE.

WILLIAM A. SWAREN, OF CHICAGO, ILLINOIS, ASSIGNOR OF THREE-FOURTHS TO THOMAS C. DOLAN, OF SAME PLACE; GEORGE E. FARRELL, OF CHARLOTTE, IOWA; JOSEPH B. WALKER, OF EFFINGHAM, ILLINOIS, AND JOHN W. DOLAN AND WILLIAM M. DOLAN, OF ELVIRA, IOWA.

VOTING-MACHINE.

SPECIFICATION forming part of Letters Patent No. 674,388, dated May 21, 1901.

Application filed September 1, 1900. Serial No. 28,735. (No model.)

To all whom it may concern:

Be it known that I, WILLIAM A. SWAREN, a citizen of the United States of America, and a resident of Chicago, in the county of Cook 5 and State of Illinois, have invented certain new and useful Improvements in Voting-Machines, of which the following is a specification.

The main objects of my invention are to 10 provide improved means in machines of this class which will permit the operator to review his intended vote and alter same by readjusting the positions of the keys at any time before the vote is registered and to provide an 15 improved arrangement of mechanism for actuating the registering devices.

The further objects of the different parts with which I put my invention into practice 20 will be understood from the following description, with reference to the accompanying drawings, in which—

Figure 1 is a top plan of a voting-machine constructed according to my invention and having the cover removed from same. Fig. 25 Fig. 2 is a vertical section on the line 2 2 of Fig. 1, including the cover. Fig. 3 is a vertical section on the line 3 3 of Fig. 1, including the cover and having the first voting-key moved to a position toward the front of the casing 30 opposite the line marked "Prohibition" in Fig. 1.

Said views show the mechanism in proper position previous to the registering of the 35 vote and when the cover of the casing is open. When the device is in this position, the operator may freely move the keys 1 along the slots 4 opposite any of the party-lines, (indicated in Fig. 1.)

The device shown consists mainly of the 40 casing 5, having a cover 6 hinged thereto at 7, the key-supporting frame or platform 8 with the movable keys thereon, the shifting frame 9, supporting the registering devices 10 and supporting the levers 11, which 45 actuate the registering devices through contact with the fingers 12 of the keys 1, and the gearing for shifting the frame 9.

The platform 8 is rigidly secured in the cas-

ing, being supported by the cross-pieces 13. A cross-piece 14 extends along and under each 50 slot 4. Each key 1 has its base 15 slidingly supported on one of said cross-pieces 14. The keys 1 are thus free to be moved along said slots and upon their respective cross-pieces 14.

The levers 11 are supported in the frame 9 55 upon shafts 16 and are movably held by the springs 17 in the position shown in Fig. 2, with the lower arms of said levers resting against the shafts 18. Each lever is provided with a pawl 19, which engages with the teeth on the 60 ratchet-wheel 20. Each wheel 10 is numbered on its periphery, as shown in Fig. 3. Said wheels 10 are loose on the shaft 18, but are sufficiently tight on said shaft to prevent same from turning except when actuated by the 65 pawl 19. Each wheel 10 has a single tooth 21, which engages with the gear-wheel 22 at each revolution of the wheel 10. The gear-wheel 22 meshes with the gear-wheel 23, which is rigidly secured to the numbered wheel 24. The 70 wheel 24 is similarly geared to the wheel 25 by means of the connecting gear-wheel 26. The gear-wheels 22 and 26 are loose on the shafts 27. The ratchet-wheels 20 are rigidly secured to the wheels 10. 75

The frame 9 is movable from left to right in Fig. 2, said frame sliding along the corner-irons 28, which are rigidly secured to the bottom of the casing and provided with slots 29, in which the screws 30 are slidable. Said 80 screws 30 are secured to the frame 9, as shown in Fig. 3. The frame is provided with cams 31 and 32, which are acted upon by the cams 33 and 34, respectively. The cams 33 and 34 are each rigidly secured to a rack 35, which 85 is longitudinally slidable in the casing. Each of said racks is moved by a gear-wheel 36, which is journaled in the casing and meshes with its respective rack. The gear-wheel 36 is connected through the intermediate gears 37, 90 38, and 39 with the toothed sector 40. The sector 40 is supported by the shaft 41 in the casing and has an arm 42 rigid thereon. Said arm has a slot 43, in which the pin 44 is slidable. Said pin is rigidly secured to the cover 6. The 95 closing of the cover will turn the gear-wheel

36 through the action of the sector 40 and the intermediate gear-wheels. This will move the racks 35 toward the rear of Fig. 1. The cam 33 will then cause the frame 9 to be moved toward the right of Figs. 1 and 2, said cam 33 acting against the cam 31. The arm 45 is rigidly connected by uprights 45' with the racks 35. Said arm 45 is thus carried along with said rack toward the right of Fig. 10 or toward the rear of Fig. 1. The arm 45 moves along the top of the platform 8 and returns the keys 1 out of voting position to the rear of Fig. 1. The arm 45 is so located with respect to the cams 33 and 31 that said 15 arm will not act against the keys 1 until after the arm 9 has been shifted so as to actuate the registers. The projection 48 is rigidly secured to the rack 35 at the left of the device and is designed to act against the 20 cam 31 to prevent any shifting of the frame 9 when the rack is in its rear position. The arm 46 is supported on some of the cross-pieces 14 and is slidably along the top of the platform 8 behind the keys 1. Said arm 46 is 25 provided with a button 47, whereby the operator may move the arm, so as to bring all of the keys 1 into any desired party-line. Thus instead of moving each of the keys separately the operator may by means of the arm 46 30 move all of the keys together to the line of any desired party.

The operation of my device is as follows: When the cover is open, the voter may move the keys 1 along the slots 4 into the desired 35 voting position. In Fig. 1 the letters A to Z, inclusive, Z^a, and Z^b indicate the different voting positions. A registering device comprising the three wheels 10, 24, and 25 is located under each of said voting positions. 40 The position of each key 1 will therefore indicate the particular registering device to be actuated. The names of the candidates will appear in the spaces indicated by the letters A to Z^b, inclusive. If, for example, the operator wishes to vote for the Republican candidate for governor, he will move the proper key 1 forward in its slot to a position adjoining the reference-letter A. He may likewise move the key for each of the other offices to 45 the positions adjoining the names of the candidates for whom he wishes to vote. Thus to vote for the Populist candidate for attorney-general the key in the slot 4 at the left of the column, which is marked "For attorney-general," will be moved forward to its position shown in Fig. 1, adjoining the reference-letter S. If the operator wishes to vote a straight party ticket, he will move the arm 46 forward, so as to bring all of the 50 keys in line with the name of the desired party. At any time before the operator begins to close the cover he may change the position of any of the keys in its respective slot. He may thus review his intended vote before 55 any of the registers are actuated. When the keys have been adjusted as desired, the operator will close the cover by swinging same

forward on its hinges 7. This will move the frame 9 through the action of the gearing and racks, as before described. When the frame 9 is moved toward the right of Figs. 1 and 2, the upper ends of the levers 11 will abut against the fingers 12 of the keys 1. This will tilt the levers 11 on their shafts 16 and turn the respective wheels 10 through 75 the action of the cams 19. At each tilting of a lever 11 its wheel 10 will be given one-tenth of a revolution. Each revolution of the wheel 10 will, through the tooth 21 and gear-wheel 22, impart one-tenth of a revolution to the 80 wheel 24. Each revolution of the wheel 24 will likewise impart one-tenth of a revolution to the wheel 25. The wheels 10, 24, and 25 represent units, tens, and hundreds, respectively. The number indicating the count 85 will be that shown by said wheels as nearest the transparent section 49 in the bottom of the casing. It will be seen that only those registers will be actuated which have one of the keys 1 located in proper position to act 90 upon the levers 11 corresponding with such registers. The bottom of the casing or the transparent section 49 will be suitably marked to correspond with the marking of candidates on the platform 8. When the cover is entirely closed upon the casing, the arm 45 will have acted upon the keys so as to move same 95 back out of voting position. When the cover is again opened, the cam 34, acting against the cam 32, will return the frame 9 to the position shown in the drawings, when the next voter may again adjust the keys. After the voting has been completed the cover will be locked down upon the casing. The vote may then be counted by turning the device bottom side up, when the votes for the different candidates may be seen through the transparent section 49 on the respective registering devices representing such candidates.

It will be understood that the details of construction of the device may be altered in many ways without departing from the spirit of my invention. I therefore do not confine myself to such details except as hereinafter limited in the claims.

What I claim as my invention, and desire to secure by Letters Patent, is—

1. A voting-machine comprising a casing having therein a series of voting-keys each adapted to be independently moved into and out of a plurality of different voting positions; a series of registering devices corresponding with said voting positions for denoting the number of votes cast; a movable cover on said casing adapted when closed to prevent access to said keys; and mechanism connected with said cover and adapted, through the closing of the cover, to actuate the registering devices corresponding with the voting positions to which said keys have been previously moved.

2. A voting-machine comprising a casing having therein a platform with a series of slots extending through said platform; a frame

within the casing supporting a plurality of registering devices along each slot and inward of the platform; a key slideable along each slot and having a handle on the outside 5 of the platform and a finger extending through its slot and adapted to have contact with any of the registering devices opposite which said key may be moved along said slot; and mechanism for changing the relative position of 10 the platform and said frame and thereby actuating the registering devices opposite which said keys have been previously moved.

3. A voting-machine comprising a casing having therein a platform with a series of slots 15 extending through said platform; a frame within the casing supporting a plurality of registering devices along each slot and inward of the platform; a key slideable along each slot and having a handle on the outside 20 of the platform and a finger extending through its slot and adapted to have contact with any of the registering devices opposite which said key may be moved along said slot; a movable cover on said casing adapted to prevent access to said keys when the cover is closed, and mechanism actuated by the closing of 25 said cover so as to change the relative position of the platform and said frame and thereby actuate the registering devices opposite 30 which said keys have been previously moved.

4. A voting-machine comprising a casing; a key-supporting frame in said casing having a series of cross-pieces, and having a platform with slots extending along and protected by 35 said cross-pieces; a key slideably mounted upon each of said cross-pieces, and movable into a plurality of different voting positions, having a handle extending outside of the platform, and a finger extending inside of 40 the platform; a frame in said casing carrying an independent registering device for each of said voting positions; said registering devices each having a connection adapted to have contact with one of said fingers, 45 one of said frames being movable in the casing relatively to the other frame, and adapted through such movement to cause said contact, and thereby actuate the registering devices corresponding with the voting positions 50 at such time occupied by said keys; substantially as described.

5. A voting-machine comprising a casing; a key-supporting frame in said casing having a platform with slots therein; a key slideable along each of said slots, into a plurality of different voting positions, and having a handle extending outside of the platform, and a finger extending inside of the platform; a frame in said casing carrying an independent 55 registering device for each of said voting positions; said registering devices each having a connection adapted to have contact with one of said fingers; one of said frames being movable in the casing relatively to the other frame, and adapted through such movement to cause said contact, and thereby actuate the registering devices corresponding with 60

the voting positions at such time occupied by said keys; substantially as described.

6. A voting-machine comprising a casing; 70 a key-supporting frame in said casing having a platform with slots therein; a key slideable along each of said slots, into a plurality of different voting positions, and having a handle extending outside of the platform, and a finger extending inside of the platform; a second frame in said casing carrying an independent registering device for each of said voting positions; said registering devices each having a ratchet-wheel for actuating same; a series of independent levers fulcrumed in said second frame, and each having a pawl for engaging one of said ratchet-wheels, and an arm for contact with one of said fingers; one of said frames being movable in the casing relatively to the other frame, and adapted through such movement to cause said contact and thereby actuate the registering devices corresponding with the voting positions at such time occupied by said keys; substantially as 80 described.

7. A voting-machine comprising a casing having a movable cover; a key-supporting frame in said casing having thereon a series of keys each independently movable into a plurality of different voting positions on such frame; a frame in said casing carrying an independent registering device for each of said voting positions; one of said frames being movable in the casing relatively to the other 100 frame; a rack longitudinally movable in the casing and having a cam bearing against and adapted to shift said movable frame; gearing connecting said cover and rack, whereby said movable frame is shifted by the closing of the cover; and connections between said keys and registering devices adapted through the shifting of said frame to actuate the registering devices corresponding with the voting positions at such time occupied by said keys; substantially as 110 described.

8. A voting-machine comprising a casing; a platform having a series of parallel slots; a key slideable longitudinally of each of said slots into a plurality of different voting positions, and having a projection extending inward of said platform; a series of independent registering devices arranged along each of said slots, inward of the platform, and normally free from said projections; one of said 115 registering devices corresponding with each of said voting positions; and a member movable in the casing relatively to said projections and adapted to connect said projections with the corresponding registering devices, 120 and thereby actuate said devices; substantially as 125 described.

Signed at Chicago, Illinois, this 27th day of August, 1900.

WILLIAM A. SWAREN.
